UNITED STATES PATENT OFFICE.

JOSO MARKUS AND LOUIS THOMAS, OF EAST PITTSBURGH, PENNSYLVANIA.

PERMUTATION LOCK.

1,420,723.

Specification of Letters Patent. Patented June 27, 1922.

Application filed November 3, 1920, Serial No. 421,500. Renewed April 12, 1922. Serial No. 551,841.

To all whom it may concern:

Be it known that we, Joso MARKUS and LOUIS THOMAS, citizens of Jugo-Slavia, residing at East Pittsburgh, in the county of 5 Allegheny and State of Pennsylvania, have invented certain new and useful Improvements in Permutation Locks, of which the following is a specification.

This invention relates to certain new and 10 useful improvements in permutation locks and one that may be readily employed as a trunk or other receptacle lock wherein a hinge member is locked to a body section.

A further object of the invention resides 15 in the provision of a permutation lock embodying a plurality of rotatable permutation disks adapted to be rotated to certain positions to permit the sliding movement of a notched bolt that is resiliently connected 20 to a keeper hook for engaging a latch member.

With the above and other objects in view, the invention consists in the novel form, combination and arrangement of parts hereinafter more fully described in connection 25 with the accompanying drawings, and in which like reference characters indicate similar parts throughout the several views.

In the drawings,

30 Figure 1 is a front elevational view of a permutation lock constructed in accordance with the present invention, a portion of a body structure and hinged cover being illustrated.

35 Figure 2 is a rear elevational view of the lock structure with the rear wall of the permutation lock mechanism casing removed, the keeper hook and latch bolt being connected.

40 Figure 3 is a rear elevational view of the lock casing containing the latch bolt, the latch bolt shown by dotted lines in retracted position.

Figure 4 is a rear elevational view, with 45 the rear wall removed of the permutation mechanism casing showing the latch keeper retracted to inoperative position.

Figure 5 is a top plan view of the latch bolt casing and a portion of the supporting 50 structure.

Figure 6 is a top plan view of the permutation lock mechanism casing with a portion of the supporting structure.

55 Figure 7 is a horizontal sectional view taken on line VII—VII of Figure 2,

Figure 8 is a perspective view of the latch keeper removed from the casing.

Figure 9 is a perspective view of the releasable member of the permutation lock mechanism, and

Figure 10 is a cross sectional view through one of the permutation disks and the spindle of the latch keeper operating member.

Referring more in detail to the accompanying drawings, there is illustrated a lock 65 for a receptacle, the receptacle embodying a body portion 1 and a hinged cover 2, a permutation lock enclosing casing 3 being secured as at 4 to the body portion 1 while a latch bolt enclosing casing 5 is secured to 70 the cover 2 as at 6.

The casing 3 containing the permutation lock mechanism is preferably rectangular in plan and has mounted therein a transverse partition 7 as shown in Figures 2 and 4 dividing the casing into compartments 8 and 9. A latch keeper operating member of the 75 form best illustrated in Figures 2, 4, and 9 is mounted within the casing 3 and comprises a spindle 10 having alined spaced lugs 80 11 extending longitudinally thereof, the spindle being slidably mounted in the partition 7 and extending into the compartment 9 while the enlarged head 12 thereof lies within the compartment 8 and engages the 85 adjacent face of the partition.

The front wall of the casing 3 is provided with an outwardly curved section 13 accommodating the curved abutments 14 on the spindle head 12 while the front wall of the 90 casing 3 in line with the curved portion 13 is provided with a longitudinal opening 15 providing a clearance for the rotatable permutation disks 16 mounted upon the spindle 10 between the partition 7 and the end wall 95 of the casing including the compartment 9. The permutation disks are of the form best illustrated in Figures 2 and 10, the same being channel-shaped in cross section defining 100 opposite walls 17 provided with central openings received on the spindle 10 with the inner walls of the openings notched as at 18 for registry with the lugs 11 to permit sliding movement of the spindle 10. When the permutation disks are rotated to displace 105 the notches from registry with the lugs 11, the side walls 17 of the permutation members extend into the spaces between adjacent lugs to cooperate therewith in holding the spindle against sliding movement. To effect 110

sliding movement of the spindle 10 and head 12 carried thereby, a pin 19 carried by the head adjacent the abutment 14 extends through a slot 20 in the front wall of the casing 3 and carries upon the projecting end thereof, a finger piece 21. A rearwardly directed arm 22 is carried by the spindle head 12 and extends through an accommodating opening in the partition 7 and is provided upon its lower face with a hook 23 for purposes presently to appear.

A sliding latch keeper of the form best illustrated in Figures 2, 4, and 8 embodies a shank 24 having a lower offset portion 25 with an overhanging keeper hook 26 and an end extension 27, a lug 28 projecting laterally from the end of the offset portion 25 for engagement with the hook 23 upon the arm 22. The shank 24 of the latch keeper is slidably mounted in a bracket 29 depending from the upper wall of the casing 3 while the end extension 27 projects through the upper end of the partition 7 and is engaged by the leaf spring 30 normally to hold the latch keeper 24 and the spindle 10 forwardly projected into the compartment 9 of the lock casing. To assist the flat spring 30, a coil spring 31 is secured to a pin 32 carried by the upper wall of the casing 3 with the end thereof secured in the opening 24' of the latch keeper shank 24, both springs 30 and 31 tending to move the latch keeper within the compartment 9.

The latch bolt contained within the casing 5 upon the cover section 2 embodies a spindle 33 carrying a latch head 34 upon its lower end with the upper end 33' thereof projecting from the upper wall of the casing 5. A pair of brackets 35 carried by one wall of the casing 5 provides sliding guides for pins 36 secured to the ends of a cross arm 37 upon the spindle 33, while a coil spring 38 surrounds the lower end of the spindle between the cross arm 37 and the bottom wall of the casing 5. The head 34 of the latch rod projects into the opening 39 of the upper wall of the casing 3 while the pins 36 are received into openings 40 in said casing wall to hold the latch bolt correctly positioned within the casing 3 and to prevent relative rotary movement of the two casings.

In the operation of the device, assuming that the lock casings are connected as shown in Figure 2, and it being desired to release the hook 26 from engagement with the head 34 of the latch rod 33, the permutation disks 16 are rotated to position the notches 18 in the walls 17 thereof for registry with the lugs 11 upon the spindle 10, at which time the finger piece 21 carried by the spindle head 12 may be shifted in the casing slot 20 to move the spindle and head and carry therewith the sliding latch keeper 24 by reason of the hook connection 23 of the

head with the lug 28 upon the latch keeper. This movement will be in opposition to the springs 30 and 31 and will displace the hook 26 from engagement with the latch head 34 whereupon the spring 38 will elevate the latch bolt and the pins 36 carried thereby to disconnect the lock sections as shown in Figure 3. Upon the release of pressure on the finger piece 21, the springs 30 and 31 will return the sliding latch keeper, spindle 10 and head 12 carried thereby to the position shown in Figure 2 to present the hook 26 for engagement with the head 34 of the latch bolt. To lock the sections together, the projecting end 33' of the latch rod is pressed downwardly against the tension of the spring 38 to project the latch head 34 into the casing opening 39 and the engaging beveled faces of the hook 36 and latch head 34 will cause the sliding latch keeper to move against the tension of the springs 30 and 31 for the complete insertion of the latch head 34 and when said hook and head are moved beyond the engaging positions of their beveled faces, the springs will return the sliding latch keeper to the position shown in Figure 2 for engagement with the head 34 of the latch rod. It will therefore be seen that it is necessary to operate the permutation disks in order to effect a positive sliding movement of the latch keeper 24 while the locking engagement between the latch bolt 33 and latch keeper 24 is automatic in view of the resilient sliding mounting of the latch keeper.

While there is herein shown and described what is believed to be the preferred embodiment of the invention, it is nevertheless to be understood that minor changes may be made therein without departing from the spirit and scope of the invention as claimed.

What is claimed as new is:

1. A permutation lock of the type described comprising a casing, a partition therein, a spindle provided with spaced lugs slidably extending through said partition, a plurality of permutation disks associated with the spindle lugs to control sliding movement of the spindle, a head carried by the spindle at the side of the partition opposite to the permutation disks, a sliding latch keeper mounted within the casing, a spring associated with each end of the latch keeper for holding the same normally projected in one direction, a keeper hook carried by the latch keeper, a lateral lug carried by the sliding latch keeper, a head carried by the spindle, a hooked arm carried by said head and in engagement with the lug on the latch keeper and a latch bolt associated with the hook of the latch keeper.

2. A permutation lock of the type described comprising a casing, a partition therein, a spindle provided with spaced lugs slidably extending through said partition, a

plurality of permutation disks associated with the spindle lugs to control sliding movement of the spindle, a head carried by the spindle at the side of the partition opposite to the permutation disks, a sliding latch keeper mounted within the casing, a spring associated with each end of the latch keeper for holding the same normally projected in one direction, a keeper hook carried by the latch keeper, a lateral lug carried by the sliding latch keeper, a head carried by the spindle, a hooked arm carried

by said head and in engagement with the lug on the latch keeper, a latch bolt casing, a tensioned latch bolt therein, guide pins carried by said bolt, the first named casing having openings in the upper wall thereof to receive the latch bolt and pins with the latch bolt in engagement with the latch keeper.

In testimony whereof we affix our signatures.

JOSO MARKUS.
LOUIS THOMAS.
